(57) **CLAIM**

The ornamental design for the lamp housing, as shown and described.

DESCRIPTION

FIG. 1 is a side elevation view of the lamp housing in accordance with our design, illustrating a possible environment for the lamp;

FIG. 2 is a top plan view of the lamp housing in accordance with our design;

FIG. 3 is a bottom plan view of the lamp housing in accordance with our design;

FIG. 4 is a front view taken along Section 4—4 of FIG. 1 of the lamp housing in accordance with our design; and,

FIG. 5 is a rear view of the lamp housing in accordance with our design and taken along Section 5—5 of FIG. 1.

The right and left elevation views are symmetrical.
